LOOM PICKER

George Brahs, Hawthorne, N. J.

Application March 6, 1934, Serial No. 714,285

3 Claims. (Cl. 139—160)

A picker for looms, made of rawhide or the like thick material which when soaked in water is responsive to shaping by pressure but which when dry is exceedingly tough, usually has the following parts whereby a tubular head to slide on a guide-rod of the loom and a shank to engage the shuttle and receive the impact of the picker-stick and be guided in a slot of the shuttle-box of the loom are formed (see the Wynne Patent No. 1,801,064): A bearing or lining member to slide on said guide-rod formed from a rectangular blank of said material having its opposite extremities extending in the same direction and spaced from each other and its mid-portion bent to the contour of a partial cylinder; a rectangular interlayer of said material forming at one edge thereof and with the bent mid-portion of said member a bore and extending from the bore between and beyond said extremities; a single strip of said material straddling said member and having its extremities receiving between them those of said member and extending beyond the same in face to face relation with said interlayer; and means, as rivets, binding together all four of said extremities and also the extremities of the strip and the interlayer where they exist face to face, the whole being molded under pressure so that the head will exist in conventional partial cylindrical form around the bore and the shank will be composed of said extremities and interlayer, being perfectly flat and of uniform thickness except where the extremities of said member exist and thus (near the head) give the shank a reinforced thickened neck.

This construction has these faults: The standard thickness of the shank of a picker is one-half inch. With the mentioned interlayer present only one ply can form each extremity thereof and the portion of the strip which immediately straddles the lining member. Consequently the part of the picker which immediately includes the head and neck is weak. Since the lining member is not endless the portion of the strip which is in the head has to withstand, practically alone, those forces which are incident to the cocking or skewing of the picker in a horizontal plane on the guide-rod incident to the action of the picker stick, wherefore said portion becomes distorted and stretched or enlarged at its ends and ceases to move truly rectilinearly on the guide-rod, and in time it may actually break apart. Another fault is that the neck, where the picker stick imparts its blow, is too weak and soon becomes distorted and deformed. Another fault is that when the parts in forming the picker are subjected to pressure the mentioned interlayer may or may not remain with its mentioned margin truly up to the perimeter of the cylinder of the bore, and if it does not it allows at the very

outset of the use of the picker the mentioned skewing to ensue.

According to this invention I overcome these faults and, in addition, provide a picker which will be self-lubricating.

In the drawing,

Fig. 1 is a plan of the picker;

Fig. 2 is a side elevation thereof;

Fig. 3 shows the lining member in sectional perspective;

Fig. 4 shows the picker in operative position; and

Figs. 5 and 6 are plans of the blanks forming the pair of strips 2 and 3 and the lining member.

For the lining member I use a rectangular blank (Fig. 6) of rawhide 1 having one edge portion turned back on itself and forming a flat fold 1a. This is bent around a suitable cylindrical core or mandrel (not shown) so that its mid-portion conforms to a cylinder and its fold-forming extremity and the opposite extremity extend in the same direction and face to face—specifically, with said edge portion in face to face contact with said opposite extremity and the bent mid-portion forming with the free margin of said edge portion a completely cylindrical bore.

Instead of the mentioned single strip and interlayer I employ two laminated strips 2 and 3 of rawhide each having the form of the blank shown in Fig. 5 and of substantially uniform thickness and which are bent around the lining member so as to straddle the same and thus flank at each side the flange or projection of said member formed by its mentioned extremities as far as they extend and then flank each other, as shown in Fig. 2. Thus, with the lining member, they form at 4 the head of the picker and where they embrace said flange and flank each other they form the picker shank 5, thickened up or reinforced as at the neck 5a. At 6 are the rivets which bind the several parts together, some penetrating all seven plies at and some penetrating the shank remote from the neck. The free end of the shank may be thickened up with rawhide, as at x, in any approved way so as to adapt it to withstand impact with the shuttle which is shown at a in Fig. 4, b being the shuttle box having the slot c in which the shank of the picker is guided, d the rod penetrating the bore of and forming a guide for the picker and e the picker stick projecting through a hole in the picker shank. On assembling the parts, of which the rawhide elements will be first softened by soaking, they are subjected to pressure to insure in particular the true cylindrical form of the head and the generally perfectly flat form of the shank with a thickness of one-half inch. An important feature here to be remarked is the fact that the outer strip 2 is thicker than the strip 3.

By the described construction I am able to

form the picker with a shank which as to its main portion (outward of the neck and between the same and part *x*) is of standard thickness (one-half inch) and all of one-half of whose thickness is continued into the neck and head of the picker to form the portion thereof which immediately straddles the lining member. Hence said portion is reinforced, or now of double thickness, and therefore effectually resists any expanding influence exerted by the guide-rod *d* on the (split) lining and the consequent distortion of the picker head, especially manifesting itself as an enlargement of the ends of the bore, and the neck is reinforced against the impacts of the picker stick and the stretching strains incident to the mentioned expanding influence of the head which naturally, if allowed to distort the head, reach into the neck of the picker. And it should not be overlooked that at each side of the mentioned flange of the lining there are in the neck two plies, of an equal thickness, of material, so that in this respect and for resisting such strains as might otherwise reach into the neck both sides of the shank are balanced in point of strength as well as weight at the neck. Moreover, by omitting the interlay and substituting a lining member which has the mentioned flange extending short of the legs of the laminated strips 2-3, when the pressure is exerted and on applying the rivets there is a tendency to crowd the flange bodily toward the mentioned mandrel, so that when the picker is completed the free margin *lb* of the edge portion *la* of the lining forms with the bent or curved portion of the latter a completely cylindrical bore, as shown in Fig. 2.

I realize that in the Gordon Patent No. 203,139 a picker is disclosed in which one-half of the four plies in the shank are continued into the head and that in the Kelly Patent No. 397,649 a fold is formed which has a margin presented to the bore in the head. But the first of these, having its lining member provided with but a two-ply flange, lacks not only desirable thickness in the neck but that resistance to skewing of the picker which is obtained when the lining member has a three-ply flange and the middle ply presents its edge at the bore; and the second of these, in which any lining assumed to exist is not an independent member but is an integral part of a single strip of which the picker is composed, has the fault that the neck of the picker at one side has but a single ply outward of the lining to withstand the friction and those strains which may reach into the neck as an incident of the tendency of the picker to skew. A factor important in the resistance of the head and neck to the forces indicated is the circumstance, as shown, that the outer of the layers 2-3 is the thicker. This not only increases the life of the picker as against the influence of friction, especially where the shank slides in the slot *c*, but it greatly exteriorly reinforces the picker as a whole. Besides, since by so much as the layer 2 is the thicker the layer 3 is decreased in thickness, the latter is the more responsive to the more acute bending which it has to undergo, which is a factor in producing and also preserving in the picker that intimacy of contact between all its component layers which is essential to its solidity, in turn an important factor in its durability.

The bent portion of the lining is provided, as at 7, with tapering apertures whose greater diameter is at the outside, and these apertures

are filled with graphite 8, or equivalent lubricating substance. When the layers or strips 2-3 are applied lubricant-containing pockets are thus formed which are only open at the inside or at the bore of the picker, wherefore when the picker slides on the rod *d* it will be self-lubricating and yet the lubricant will not be wastefully drawn out of the pocket by the rod. This feature of my invention applies to any picker comprising, with a part forming a passed head (as here the straddling or rebent portion of the strips 2-3) and the shank, a lining member having a portion thereof snugly fitting the passage of said part and provided with the defined apertures and a solid lubricant 15 therein.

Having thus fully described my invention what I claim is:

1. A loom picker comprising a lining member formed from a generally rectangular blank of stiff thick sheet material having one edge portion turned back and the fold thus resulting forming one extremity of the member, said member having said extremity and the opposite extremity thereof projecting in the same direction with said edge portion in face to face contact with said opposite extremity and having its mid-portion bent to the contour of a cylinder and forming with the free margin of said edge portion a completely cylindrical bore, a pair of laminated strips of said tough thick sheet material each of substantially uniform thickness straddling said member and having their extremities receiving between them the extremities of said member and extending beyond them in face to face relation to each other and forming therewith the picker shank, and securing devices penetrating all four extremities and also the extremities of the strips where they exist face to face with each other.

2. A loom picker comprising a lining member formed from a generally rectangular blank of stiff thick sheet material having one edge portion turned back and the fold thus resulting forming one extremity of the member, said member having said extremity and the opposite extremity thereof projecting in the same direction with said edge portion in face to face contact with said opposite extremity and having its mid-portion bent to the contour of a cylinder and forming with the free margin of said edge portion a completely cylindrical bore, a pair of laminated strips of said tough thick sheet material each of substantially uniform thickness straddling said member and having their extremities receiving between them the extremities of said member and extending beyond them in face to face relation to each other and forming therewith the picker shank, the relatively outer strip being the thicker of the two strips, and securing devices penetrating all four extremities and also the extremities of the strips where they exist face to face with each other.

3. In combination, with the part of a loom picker including a head and a shank, the head having a passage therethrough to receive the loom guide-rod, a lining member having a portion thereof snugly fitting said passage and having an aperture penetrating said portion from its said passage to said lining and closed at its outer end by the head and having greater diameter at its outer end than at its other end, and a mass consisting wholly of lubricant in solid form filling said aperture.
